UNITED STATES PATENT OFFICE.

PAUL A. STOVER, OF RACINE, WISCONSIN, ASSIGNOR TO THE STOVER SIGNAL ENGINEERING COMPANY, OF RACINE, WISCONSIN, A CORPORATION OF DELAWARE.

DESIGN FOR A COMBINATION TAIL AND STOP LAMP.

Application filed May 29, 1924. Serial No. 9,736. Term of patent 14 years.

To all whom it may concern:

Be it known that I, PAUL A. STOVER, a citizen of the United States, residing at Racine, Wisconsin, have invented a new, original, and ornamental Design for Combination Tail and Stop Lamp, of which the following is a specification, reference being made to the drawing forming a part thereof.

In the annexed drawing, Fig. 1 is a front view, and Fig. 2 is a side elevation of my new tail and stop lamp.

I claim:

The ornamental design for a combination tail and stop lamp as shown.

PAUL A. STOVER.
